HOUSING FOR SPACE HEATERS AND SOUND
TRANSLATORS

David Sandler, Cleveland Heights, Ohio

Application May 10, 1949, Serial No. 92,309

8 Claims. (Cl. 181—31)

1

This invention relates to housings and particularly to a housing for a space heater and an associated sound translator.

Conducive to a better understanding of this invention it may be well to point out that outdoor motion picture theaters, or so-called "drive-in" theaters, have become very popular within the last ten to fifteen years.

These theaters have specially constructed car ramps upon which the theater-goer drives his own automobile and views the motion picture screen while seated in his own car.

The sound accompanying the motion picture is brought to the spectator by means of individual sound translators or loud-speakers, that are hung from the door or window of each car.

In the past the lack of suitable heating facilities has limited the operation of such drive-in theaters to the warmer months of the year, thereby materially reducing the possibility of recovering an adequate return on the capital investment involved. Attempts have been made to provide separate space heaters for each car. However, this usually meant the handling of another unit in each car, in addition to the speaking unit, which was found to be unsatisfactory both from the standpoint of economical operation and safety.

The primary object of this invention therefore is to provide a housing for an associated space heater and sound translator that is both compact and portable.

Another object is to provide a housing for a combined space heater and sound translator that can be hung from the door or window of an automobile that is parked in a drive-in theater, whereby the interior of the automobile is heated to a comfortable temperature by the space heater while the sound translator acts to deliver sound synchronized with the picture being viewed by the occupants of the automobile.

A further object is to provide a housing of the type stated whose structure is such that space heating and sound translating elements may be closely associated therein, without danger of damage to the sound translator due to the heat radiated by the space heating element.

Still another object is to provide a housing of the type stated that is simple in structure, economical to manufacture and well adapted for the purposes described.

These and other objects of the invention will become apparent from a reading of the following specification and claims together with the accompanying drawing wherein:

2

Figure 1 is a front elevation of the housing with a portion of the front wall broken away to disclose the relative position of the ceramic box and the sound translator;

5 Figure 2 is a right end view of the housing partly in section, showing the relative positions of the space heater and the sound translator;

Figure 3 is a rear view of the same, with a portion broken away, taken substantially along the line end in the direction of the arrows 3—3 of the Figure 2; and

Figure 4 is a plan view of the housing with a portion broken away and showing the ceramic box member partly in section.

15 The preferred form of the housing, as shown in the drawing, comprises a hollow case member and a ceramic box member mounted therein and broadly indicated by the reference characters 10 and 20 respectively.

20 The case member 20 is made of two nested sheet metal shells, 11 and 12 attached together at their brims by screws 18 as shown in the Figures 1, 2, 3 and 4. The assembled housing measures approximately eight inches by six inches by three and one-quarter inches and therefore is very compact and easily placed within an automobile for the convenience of the persons seated therein.

25 The front wall or shell 11 has a first opening 13 that is approximately circular in shape. This opening is protected by downwardly directed louvers 14 that are pressed from and integral with the front shell 11. Inwardly extending bolts 37 are welded to the front wall 11 proximate to the periphery of the opening 13. A sound translator or loud-speaker 35 is mounted on the said front wall at the opening 13 by means of the bolts 37 as is shown in the Figures 1, 2, and 3.

30 The sound translator or loud-speaker 35 may be of any suitable type and in the preferred form shown consists of a four inch cone-type speaker having a permanent magnet, which has been found to be the most rugged type for out-door use.

35 The leads 36 of the speaker are connected through the usual cables to the sound reproducing system of the theater. A volume control switch, not shown in the drawing and forming a part of the speaker circuit, is mounted in the housing and may be operated by the listener to adjust the volume of the speaker to any desired level, as is well known in the art.

40 The front wall 11 has a second approximately rectangular opening 15 directly above the first opening 13, as is shown in the Figures 1 and 2 of the drawing.

A ceramic box 20 is mounted in the second opening 15. The ceramic box 20 is made of vitrified clay having low thermal conductivity, and is molded as a one piece unit with integral front and side walls, 21 and 22 respectfully. The box 20 is circular in cross-section and has an open rear as shown in the Figures 2, 3 and 4. In the preferred form shown, the ceramic box is approximately three and one-half inches in diameter, one and three-eighths inches deep and has side walls one-eighth inch thick. 10

The front wall 21 has a series of transverse vents 23 that are protected by downwardly directed louvers 24; the louvers being also molded integral with the front wall. Reference character 25 indicates an integral shoulder on either side of the ceramic box having mounting holes 26 therethrough.

The ceramic box 20 is mounted in the case, on the front wall thereof, with the air vent louvers 24 extending through the second opening 15. The box 20 is held in place by means of threaded bolts 27 that pass through the mounting holes 26 of the shoulder 25. A resistance heating element 40 rated at two hundred and fifty watts, one hundred and ten volts is mounted in the box 20 directly behind the louvered vents 23 as shown in the Figures 2 and 3. The heating element 40 is circular in shape and has mounting leads 42 that pass through a hole 28 on the side wall 22 and under a mounting block 41 located on the outside of the box 20 as shown in the Figures 3 and 4. A threaded bolt 32 is used to anchor the heating element 40 in place. 20

A motor driven fan 30 is mounted on the back shell 12 by means of threaded bolts 34 which engage the motor frame 31. The fan 30 is approximately three inches in diameter and is positioned within the ceramic box immediately to the rear of the heating element 40 as shown in the Figures 2 and 4. 30

The motor leads 33 and the heating element leads 43 are connected to a switch, not shown in the drawing, that controls the operation of the fan and heater simultaneously, thereby preventing the energization of the heater element 40 unless the fan 30 is also in operation to dissipate the intense heat created by the element 40. 40

The back shell 12 has louvered openings 19 formed integral therewith, through which cold air is drawn by the operation of the fan 30. Reference character 16 indicates a rearwardly and downwardly extending hanger that is mounted on the back shell 12. This hanger is used to support the housing from the window or door of an automobile. A handle 17 is mounted on the top of the case and serves as a lifting means for moving the housing from place to place. 50

By referring to the Figures 1 and 2 it will be seen that the lower portion of the ceramic box 20 is slanted toward the rear to enable the top edge of the speaker 35 to be positioned nearer to the second opening 15, thus permitting the case to be made smaller and more compact. 60

This compact arrangement is possible by reason of the fact that the continuous side wall 22 of the ceramic box 20 is positioned between the heater element 40 and the speaker 35 and acts as a protective heat insulator for the speaker 35 which would otherwise be damaged by the heat generated. 70

The position of the heater element 40 in the front portion of the ceramic box 20 immediately behind the louvered air vents 24 causes most of the heat created to escape from the ceramic box 75

Any rearwardly projected heat is absorbed by the stream of cool air that is drawn through the air inlets 19 by the fan 30 and blown out through the louvered vents of the ceramic box 20, after passing through the box 20 and over the heater element 40. In passing over the heater element 40, the air cools the heater element and is, in turn, further warmed by the absorbed heat. 5

A blast of heated air is thus blown through the louvered openings 24 into the interior of the car, which is speedily brought to a comfortable temperature. 15

The tunnel-like shape of the ceramic box 20 confines the heat generated to the interior of the box, from which it is speedily removed by the air blast created by the fan 30. 20

The interior of the hollow case 10 is kept cool by the fresh air drawn in through the air inlets 19, while the side wall 22 of the ceramic box 20 protects the speaker from the damage due to direct radiation from the resistance heater 40. 25

The manner of constructing the housing just disclosed permits a sound translator and space heater to be closely positioned within a single compact portable unit without danger of destroying the sound translator due to the proximity of the space heater. 30

It will now be clear that there is provided a device which accomplishes the objectives heretofore set forth. While the invention has been disclosed in its preferred form; it is to be understood that the specific embodiment thereof as described and illustrated herein is not to be considered in a limited sense as there may be other forms or modifications of the invention which should also be construed to come within the scope of the appended claims. 40

I claim:

1. A housing of the type adaptable for use with a space heater element and an associated sound translator, comprising in combination, a hollow case member including a wall portion, the said wall portion having a first opening therein and having means for supporting the aforesaid sound translator thereat, the said wall portion also having a second opening proximate to the said first opening, and a ceramic box member including a front and a side portion and adapted to contain the aforesaid heater element therein, the said front portion having air vent louvers extending through the said second opening, the said side portion having a shoulder engageable with the said wall portion proximate the second opening, the said box member side portion being between the sound translator and the heater element and thereby insulating the former from the latter. 50

2. A housing of the type adaptable for use with a space heater element and an associated sound translator, comprising in combination, a hollow case member including a wall portion, the said wall portion having a first opening therein and having screw means for supporting the aforesaid sound translator thereat, the said wall portion having a second opening proximate to the said first opening, and a ceramic box member including a front and a side portion and adapted to contain the aforesaid heater element therein, the said front portion having air vent louvers extending through the said second opening, the said side portion having a shoulder engageable with the said wall portion proximate the second open- 60

ing, the said box member side portion being between the sound translator and the heater element and thereby insulating the former from the latter.

3. A housing of the type adaptable for use with a space heater element and an associated sound translator, comprising in combination, a hollow case member including a wall portion, the said wall portion having a first opening therein and having means for supporting the aforesaid sound translator thereat, the said wall portion also having a second opening proximate to the said first opening, and a ceramic box member including integral front and side portions, and adapted to contain the aforesaid heater element therein, the said front portion having air vent louvers extending through the said second opening, the said side portion having a shoulder engageable with the said wall portion proximate the second opening, the said box member side portion being between the sound translator and the heater element and thereby insulating the former from the latter.

4. A housing of the type adaptable for use with a space heater element and an associated sound translator, comprising in combination, a hollow case member including a wall portion, the said wall portion having a first opening therein and having means for supporting the aforesaid sound translator thereat, the said wall portion also having a second opening proximate to the said first opening, and a ceramic box member including a front and a side portion and adapted to contain the aforesaid heater element therein, the said front portion having air vents parallel to the plane of the second opening, the said side portion having a shoulder engageable with the said wall portion proximate the second opening, the said box member side portion being between the sound translator and the heater element and thereby insulating the former from the latter.

5. A housing of the type adaptable for use with a space heater element and an associated sound translator, comprising in combination, a hollow case member including a wall portion, the said wall portion having a first opening therein and having screw means for supporting the aforesaid sound translator thereat, the said wall portion also having a second opening proximate to the said first opening, and a ceramic box member including integral front and side portions, and adapted to contain the aforesaid heater element therein, the said front portion having air vents parallel to the plane of the second opening, the said side portion having a shoulder engageable with the said wall portion proximate the second opening, the said box member side portion being between the sound translator and the heater element and thereby insulating the former from the latter.

6. A housing of the type adaptable for use with a space heater element and an associated sound translator, comprising in combination, a hollow case member consisting of front and back nested shells attached together at their brims, the said front shell having a first opening therein and having means for supporting the aforesaid sound translator thereat, the said front shell also having a second opening proximate to the

said first opening, the said back shell having an opening therein, and a ceramic box member including integral front and side portions, and adapted to contain the aforesaid heater element therein, the said front portion having air vent louvers extending through the said second opening, the said side portion having a shoulder engageable with the said front shell proximate the said second opening, the said box member side portion being between the sound translator and the heater element and thereby insulating the former from the latter.

15 7. A housing of the type adaptable for use with a space heater element and an associated sound translator, comprising in combination, a hollow case member consisting of front and back nested shells attached together at their brims, the said front shell having a first opening therein and having means for supporting the aforesaid sound translator thereat, the said front shell also having a second opening proximate to the said first opening, the said back shell having an opening therein and a hanger portion extending rearwardly thereof, and a ceramic box member including integral front and side portions, and adapted to contain the aforesaid heater element therein, the said front portion having air vent louvers extending through the said second opening, the said side portion having a shoulder engageable with the said front shell proximate the said second opening, the said box member side portion being between the sound translator and the heater element and thereby insulating the former from the latter.

35 8. A housing of the type adaptable for use with a space heater element and an associated sound translator, comprising in combination, a hollow case member consisting of front and back nested shells attached together at their brims, the said front shell having a first opening therein and having screw means for supporting the aforesaid sound translator thereat, the said front shell also having a second opening proximate to the said first opening, the said back shell having an opening therein and a hanger portion extending rearwardly thereof, and a ceramic box member including integral front and side portions and adapted to contain the aforesaid heater element therein, the said front portion having air vents parallel to the plane of the second opening, the said side portion having a shoulder engageable with the said front shell proximate the said second opening, the said box member side portion being between the sound translator and the heater element and thereby insulating the former
